UNITED STATES PATENT OFFICE

121,098

DESIGN FOR A PROJECTOR

Harold Osterberg, Buffalo, and Charles M. Sperazz, Kenmore, N. Y., assignors to Spencer Lens Company, Buffalo, N. Y., a corporation of New York

Application March 29, 1940, Serial No. 91,332

Term of patent 14 years

To all whom it may concern:

Be it known that we, Harold Osterberg and Charles M. Sperazz, citizens of the United States of America, residing at Buffalo and Kenmore, respectively, in the county of Erie and State of New York, have invented a new, original, and ornamental Design for Projectors, of which the following is a specification, reference being made to the accompanying drawing, forming a part thereof.

Fig. 1 is a front perspective view of a projector showing our new design;

Fig. 2 is a plan view of the same as disclosed in Fig. 1; and

Fig. 3 is a front view of the same as disclosed in Fig. 1 and Fig. 2.

The characteristic features of the design are shown in full lines in the drawing.

We claim:

The ornamental design for a projector, substantially as shown and described.

HAROLD OSTERBERG.
CHARLES M. SPERAZZ.
